UNITED STATES PATENT OFFICE

HARRY ARTHUR FOOTHORAP, OF HARRISBURG, PENNSYLVANIA, ASSIGNEE TO
ELLIOTT-FISHER COMPANY, A CORPORATION OF DELAWARE

KEY AND ACTUATOR LOCK FOR WRITING ADDING MACHINES

Application filed December 31, 1920. Serial No. 434,252.

This invention relates to writing adding machines, and has for its object to equip a machine of this character with key locking mechanism which automatically controls the 5 operation of the keys in accordance with the operating requirements of the adding mechanism.

Another object of the invention is to utilize the key locking mechanism as an element 10 of a full-stroke mechanism to insure a complete or full stroke operation of an element of the adding mechanism, as for instance, the restoring member thereof, by retaining the keys in locked condition until the complete 15 restoring operation has been effected and all parts returned to normal position.

Another object is to provide for throwing the adding mechanism entirely out of action so that the machine may be used independently thereof, the mechanism whereby this 20 object is accomplished, having such relation to key locking and full-stroke mechanisms that the operative requirements of each shall be met. To the accomplishment of these objects and others subordinate thereto, one embodiment of the invention is that to be hereinafter described, illustrated in the drawings and succinctly defined in the appended claims.

In said drawings:

30 Figure 1 is a front elevation of a portion of what is known to commerce as an Elliott-Fisher billing machine having my invention applied thereto.

Figure 2 is a plan view with the parts in 35 normal position.

Figure 3 is a front elevation of the subject-matter of Figure 2.

Figure 4 is a view similar to Figure 2 but showing the parts in the positions they assume 40 when the master wheel has moved through the register.

Figure 5 is a front elevation of the subject-matter of Figure 4.

Figure 6 is a side elevation showing more 45 particularly the restoring lever of the cross-footer, the two master wheel locks, and associated elements of the full-stroke mechanism.

Figure 7 is a view similar to Figures 2 and 4 with the parts in the positions they assume 50 when the cross-footer has been put out of

action by the movement of the master wheel beyond the normal limit of its traversing movement.

Figure 8 is a front elevation of the subject-matter of Figure 7. 55

Figure 9 is a detailed view of the lock which retains the master wheel in the position shown in Figures 7 and 8.

Figure 10 is a view similar to Figure 6 with the restoring lever fully depressed and 60 the associated master wheel lock in unlocked position.

Figure 11 is a detailed sectional view of a portion of the key locking mechanism.

Figure 12 is a detailed section at right angles to the section in Figure 11. 65

The subject-matter of this invention has been designed with special reference to the Elliott-Fisher bookkeeping machine of commerce, and while a disclosure of the entire 70 machine is unnecessary for the present purpose, it may be briefly stated that this type of machine includes in its usual organization, a flat platen which supports the work sheet, and a printing mechanism which moves 75 longitudinally of the platen for line spacing and transversely thereof for letter spacing. The printing mechanism is mounted on a carriage which travels transversely of the platen on a line space frame which travels longitudinally of the platen. This relative movement of the carriage with respect to the line space frame is utilized to advance a master 80 wheel mounted on the carriage, into operative relation with successive number wheels 85 of one or more adding devices or registers which are mounted back of the carriage on the line space frame. Between the master wheel and the keys of the printing mechanism an actuating mechanism is mounted to cause the rotation of the master wheel a number 90 of increments corresponding to the value of the key depressed. Thus, when a number is printed on the work sheet in a given denominational position of the column, the master wheel accumulates a corresponding 95 value in the number wheel of corresponding denominational position.

Also, it is common in these machines to mount at one end of the carriage an additional 100

computing device generally termed a cross-footer. The cross-footer has its own master wheel which moves back and forth across an adjacent series of number wheels and is rotated from and in synchronism with the primary master wheel before mentioned. With this general understanding in mind, we may now proceed with the description of the illustration which has been deemed necessary 10 for the purpose of this particular disclosure.

1 indicates the carriage of the machine, 2 the adding keys and 3 the key levers which, when swung down by the operation of the keys, effect the rotation of the primary master 15 wheel, not illustrated, and the cross-footer master wheel 4. Mounted between the key levers 3 are a series of key locking members which, unless obstructed, will swing laterally to afford a passage for the key lever which 20 is depressed, it being understood that when a key lever has passed between two of the locking members, all of the other locking members of the series will obstruct all of the other keys, thus preventing the operation of 25 more than one key at a time. This construction and arrangement is well understood.

My present invention, however, contemplates the utilization of the locking members 30 5 for the locking of all of the keys so that under certain conditions it will be impossible to operate the adding mechanism. This end is attained by removing one of the members 5 from the series and in substituting there- 35 for a pair of locking members 6 swung from their upper ends and having interposed between them what may be termed a spreader 7, located at one end of a spreader shaft 8, mounted in a suitable bearing 9, and having 40 secured at its opposite end a crank 10 by means of which the spreader shaft may be turned. Normally, the spreader occupies the inactive or unlocked position indicated in Figures 3 and 8, and does not obstruct the 45 spreading of any pair of locking members 5 by a descending key lever.

Under other conditions to be more fully explained, the spreader occupies the effective or locked position best shown in Figure 12, 50 and prevents the locking members from yielding to permit the downward movement of a key lever. A spring 11 tends to rotate the spreader shaft 8 in the direction to unlock the keys and the movement of the crank 10 in either direction is limited by a stop bracket 12 which is engaged by the crank pin 13. Fulcrumed intermediate of its ends on the bracket 12, is a spreader operating lever 14, bifurcated at its upper end to engage the pin 60 13, and pivoted with a stud 15 adjacent to its angular lower end 16 which is perforated to receive one end of a link 17 connected at its opposite end to a lever 18. The lever 18 is provided with a beak 19 designed to be engaged by the upper end of what may be

70 termed a full-stroke lever 20 mounted on one side wall of the cross-footer 21. At its lower end the lever 20 is provided with an arcuate slot 22 having an offset portion 23. The slot 22 is engaged by a pin 24 extended from the cross-footer restoring lever 25, fulcrumed at its rear end as indicated at 26 and provided at its front end with a restoring key 27. As thus far described, the mechanism for locking the keys appears in the aspect of a full 75 stroke device for the restoring lever of the cross-footer.

75 It may be noted in passing, that in the usual construction of the cross-footer, the carrying mechanism which is operated during the adding operation must be reset or restored before another number is thrown into the cross-footer, and it will be seen that those elements of the mechanism thus far described provide for the locking of the keys and prevent the operation of the machine as long as the restoring lever is out of normal position. In this sense, the mechanism constituted a full-stroke device for the mechanism which restores the cross-footer to normal 80 carrying condition. This will be understood better by reference to Figures 6 and 10 of the drawings.

85 The first downward movement of the restoring lever 25 causes the pin 24, by traversing the offset 23 of the slot 22, to swing the lower end of the full stroke lever 20 forward and the upper end thereof in a rearward direction. As the upper end of this lever is in 90 position to engage the beak 19 of the lever 18, said lever will be swung and through the intermediate link 17 will swing the spreader operating lever 14 which by engagement with the crank 10 will rotate the spreader shaft 8, and swing the spreader 7 to the locked 95 position shown in Figure 12. The adding keys will now be locked against actuation; the continued downward movement of the restoring lever 25 will be permitted, as the pin 24 will pass down along the arcuate portion of the slot 22 which is concentric with the fulcrum 26 of the restoring lever.

100 Obviously, the full-stroke lever 20 cannot return to its normal position until the restoring lever is again returned to normal, at 105 which time the entrance of the pin 24 into the offset 23 of the slot will return the lever 20 to normal position and allow the spring 11 to retract the spreader to its unlocked position. The action of the spring 11 is preferably augmented by a spring 28, secured to the lower end of the spreader operating lever 14, and to a fixed part.

110 The key locking mechanism, in addition to this function as a full stroke device, is intended to prevent the operation of the machine after the cross-footer master wheel has moved beyond the last number wheel of the cross-footer series. The cross-footer 21 includes in its organization a series of number 115 120 125 130

wheels 29 across which the master wheel 4 is advanced by a master wheel advancing mechanism including a vertical shaft 30 having oppositely extending arms 31 and 32. 5 The arm 31 engages a pin 33 extended from a master wheel carriage 34 movable along a guide 35 and engaging the hub of the master wheel 4 to move the wheel along its squared shaft 36 driven from the adding keys in the 10 usual manner. The function of the arm 32 will presently appear.

Connected to the carriage 34 and extended through the side walls of the cross-footer frame to permit its movement with the carriage, is a cross-footer carriage bar 37 having its left hand extremity threaded and extended through a flange 38 at one end of a slide 39 suitably guided as indicated at 40 and 40A, and having its rear end 41 upturned to form 15 a projection adapted to engage the stud 15 (see Figure 11), and thus swing the lever 14 to present the spreader 7 in the locking position as indicated in Figure 5. The threaded end of the carriage bar 37 is not 20 secured to the flange 38, but merely passes therethrough, and is equipped at opposite sides of the flange with nuts 42 and 43, between the latter of which and the flange 38 is interposed a spiral spring 44 which permits 25 limited movement of the slide 39 independently of the bar 37 under certain conditions. Normally, that is to say, before the adding operation is commenced, the parts occupy the positions shown in Figures 2 and 3. The master wheel 4 is to the left of the number wheels, the slide 39 is at one limit of its movement, and the spreader is in the inactive position so that the keys are unlocked to permit the operation of the machine. The 40 arm 32 of the master wheel advancing mechanism is in position to be arrested by a controlling device 45 mounted as usual on the line space frame, and the next advance of the carriage will move the master wheel 4 into 45 engagement with the number wheel of highest order. A number may now be written and accumulated in the cross-footer, but as the master wheel moves into mesh with the last number wheel of the series, the master 50 wheel carriage bar 37 will have advanced the projection 41 of the slide 39 into engagement with the lever 14 and will have moved the parts of the key locking mechanism sufficiently so that upon the next advance of the 55 master wheel, to the first position beyond the number wheels, the spreader 7 will have become effective to lock the keys. Thus, another object of the invention, to wit: the 60 locking of the keys when the master wheel moves out of the register will have been accomplished. This operation of the key locking mechanism to lock the keys will not affect the full-stroke lever 20, because the link 17 65 will merely swing the lever 18 idly, since said

lever is not positively connected to the full stroke lever 20.

In the usual operation of the machine, the operator should now depress the restoring lever of the cross-footer to restore the carrying mechanism, since the arm 32 will have passed the control device 45 and have permitted the cross-footer master wheel to be retracted to the left of the register by its retracting spring 46. In accordance with my invention, however, it is the purpose as heretofore stated, to lock the adding keys and to keep them locked from the time the master wheel moves out of the register until the restoring lever returns to normal position after a complete operation. This would not be possible if the master wheel were permitted to retract immediately after moving out of the register, because, this consequent operation of the full-stroke mechanism, would result in the immediate unlocking of the keys and the possible operation of the machine before the cross-footer had been restored. I therefore effect the locking of the master wheel, when one increment to the right of the number wheels, 85 and hold it locked until released by the operation of the cross-footer restoring lever which, when once in motion is protected by the full-stroke mechanism against an incomplete operation. This is because the keys 90 locked by the advance of the master wheel will be held locked by the full-stroke mechanism after the master wheel is released and retracted, and until the restoring lever moves back to its normal position. A locking plate 100 47 is mounted to slide upon suitable guides 48 to present its upper extremity in a notch 49 formed in the under side of the carriage bar 37, when the master wheel moves beyond the number wheels. The locking plate 47 is 105 constantly urged toward its locking position by a spring 49A, and at its lower end is provided with an arcuate slot 50 concentric with the axis of the restoring lever 25. The slot 50 receives the pin 24, which is designed, 110 when the restoring lever is fully depressed, to engage the lower end of the slot, and draw back the locking plate 47 to release the carriage bar 37, and permit the retraction of the master wheel by the spring 46. It will 115 now be seen that when the master wheel moves from the position shown in Figures 2 and 3 to that shown in Figures 4 and 5, the slide 39 will have caused the locking of the keys and the locking plate 47 will have engaged the bar 37 to hold the master wheel against retraction, and to thereby maintain the key locking mechanism in effective position. This inoperative condition of the machine will continue until the restoring lever 120 25 is depressed. When said lever is completely depressed, the locking plate 47 will release the bar 37 and the master wheel will be immediately retracted to the left of the register. This will shift the slide 39 to its 125 130

normal position shown in Figure 2. The unlocking of the keys will not result, however, because we have seen that as long as the lever 25 is out of normal position, the full-stroke 5 lever will be held in such position that the spreader will be prevented from returning to its unlocked position, because such movement would necessitate a movement of the lever 18 which is blocked by the full stroke lever. As soon however, as the restoring lever moves back to normal position the keys 10 are unlocked and the cross-footer is ready for operation.

A further feature of the invention 15 templates the placing of the cross-footer out of action. To accomplish this end, provision is made for moving the master wheel one step or increment beyond the normal limit of its movement to the right. We have 20 seen that when the master wheel moves beyond the register, the keys are locked by the operation of the slide 39, and the master wheel is locked against retraction by the locking plate 47.

25 Attention is now directed to the fact (see Figure 3) that the notch 49 is of sufficiently greater width than the plate 47 to permit the bar 37 to move to the right one additional increment or step after being engaged by the 30 lock. This additional advance of the master wheel to the second position beyond the register is effected manually by means of a key or handle 51, and its retraction from this position is prevented by a pivoted lock 52 engaging a notch 53 in the bar 37 and urged toward its locking position by a spring 54. When the master wheel is shifted over to the 35 extreme right hand position, the lock 52 springs into action, but may be released at the proper time to permit the retraction of the master wheel by depressing what is known as the cross-footer release key 55 carried by the lock 52.

There are two requirements which must be 40 met in connection with this extraordinary movement of the master wheel to cut out the cross-footer; first, the unlocking of the keys so that the machine may be freely used for writing or for writing and adding as a simplex machine, by which is meant a machine operated for plain addition and subtraction without cross-footing; and second, locking of the keys when the master wheel, upon the operation of the cross-footer release, 45 has moved back again to a position one step beyond the number wheels, so that, if the cross-footer has been left unrestored, it will of necessity be restored before the operation of the machine can be again effected.

50 To meet these requirements, a simple mechanism has been devised for unlocking the keys when the wheel is moved the extraordinary step, and for locking the keys as soon as it moves back one step. As shown in Figure 2 and Figure 5, an unlocking lever 56 is

provided with a pin 57 with which the nut 42 on the bar 37 contacts when the master wheel moves out of the register. (See Figure 4.) The slide 39, which has locked the keys, is, in this position, disposed closely adjacent to the other end of the lever 56. Thus, when the master wheel is moved over one increment to the right, the nut 42 will swing the lever 56 and thus push back the slide 39 against the resistance of the spring 44 to permit the keys to unlock. This relation of the parts will be maintained as long as the master wheel is held out of action by the lock 52, and the machine may be used for writing or writing and adding independently of the cross-footer. Upon the operation of the cross-footer release key 55, however, the master wheel will be permitted to move back to the extent permitted by the slight enlargement of the notch 49, and incidently withdrawing the nut 42 from the pin 57 and thus permitting the spring 44 to restore the slide 39 to its normal locked position. The keys will now be locked again and will remain locked until the restoring lever has been fully depressed and retracted to normal position in the manner before described.

What I claim is:

1. In a machine of the class described, the combination with a traveling series of adding keys, and an adding mechanism including a series of number wheels and a master wheel, a key locking mechanism, and means movable with the master wheel to cause the key locking mechanism to lock the keys when the master wheel advances beyond the number wheels. 95

2. In a machine of the class described, the combination with a series of keys, and an adding mechanism including a series of number wheels and a laterally movable master wheel, of key locking mechanism, and means controlled by lateral movement of the master wheel for causing the key locking mechanism to lock the keys when the master wheel has moved to a pre-determined position and to unlock the keys when the master wheel moves from said position in either direction and means for preventing unlocking of the keys by the movement of the master wheel under certain conditions. 105

3. In a machine of the class described, the combination with a series of keys, an adding mechanism including denomination selecting mechanism, and transfer restoring mechanism, of key locking mechanism effective to lock the keys when the denomination selecting mechanism is moved to a given position, and means operated by the restoring mechanism to effect the unlocking of the keys as an incident to movement of the denomination selecting mechanism to another position. 115

4. In a machine of the class described, the combination with a series of keys, an adding mechanism including a master wheel car- 120

130

riage, and restoring mechanism, of means movable with the master wheel carriage to effect the locking of the keys, means for locking the master wheel carriage against retraction, and means whereby the restoring mechanism will effect the release of the master wheel carriage for retraction and accomplish the unlocking of the keys.

5. In a machine of the class described, the combination with a series of keys, an adding mechanism including a master wheel carriage, and a transfer restoring mechanism, of key locking mechanism under the joint control of the master wheel carriage and the restoring mechanism, whereby said key locking mechanism will lock the keys when the master wheel carriage moves to a pre-determined position and will retain said keys in locked condition until the restoring mechanism has been completely operated.

6. In a machine of the class described, the combination with a series of keys, and an adding mechanism including transfer restoring mechanism and denomination selecting mechanism, of means for locking the keys during the operation of the restoring mechanism and for unlocking said keys under control of the denomination selecting mechanism when the restoring mechanism has been completely operated.

7. In a machine of the class described, the combination with a series of keys, and an adding mechanism including denomination selecting means, of means for locking the keys when the denomination selecting means reaches a given position, means for moving the denomination selecting means beyond said position, said means operating to unlock the keys, and a locking device movable to lock the selecting means in its most advanced position and to release said means.

8. In a machine of the class described, the combination with a series of keys, and an adding mechanism including a laterally movable master wheel, of means for locking the keys when the master wheel moves to an inoperative position, means for moving the master wheel beyond such position and for unlocking the keys, and means for locking the master wheel in the position last named.

9. In a machine of the class described, the combination with a series of keys, of an adding mechanism including a laterally movable master wheel, retracting mechanism therefor, and a restoring mechanism, of means for locking the keys and for locking the master wheel against retraction when said master wheel moves to a pre-determined position, said restoring mechanism being operative to release the master wheel for retraction and to effect the unlocking of the keys.

10. In a machine of the class described, the combination with a series of keys, and an adding mechanism including a series of number wheels, a laterally movable master wheel, and

a restoring mechanism, of key locking means operative when the master wheel moves to a given position, a locking device for preventing the retraction of the master wheel from said position, means whereby the restoring mechanism will effect the release of the master wheel for retraction, and means preventing the unlocking of the keys until the operation of the restoring mechanism has been completed.

11. In a machine of the class described, the combination with a series of keys, and an adding mechanism including a series of number wheels, a laterally moving master wheel, and a restoring mechanism, of two master wheel locks, one for locking the master wheel against retraction from a given position and the other for locking the master wheel in its extremely advanced position, means for locking the keys when the master wheel moves to the given position aforesaid, and for unlocking the keys when the master wheel has moved to its extreme position, a key for releasing the master wheel from its extreme position, means whereby the restoring mechanism will release the master wheel from said given position, and means preventing the unlocking of the keys until the operation of the restoring mechanism is completed.

12. In a machine of the class described, the combination with a series of adding keys, and an adding mechanism, including number wheels, a laterally movable master wheel, and a restoring lever, of means for locking the master wheel against retraction and the keys against operation when the master wheel passes beyond the number wheels, means for releasing the master wheel for retraction when the restoring lever is completely depressed, and means for unlocking the keys when the restoring lever returns to normal position.

13. In a machine of the class described, the combination with keys, and adding mechanism including an actuator movable into different denominational positions, of key locking mechanism including a lock, and a lock actuating member set into lock actuating position by movement of the actuator into the units selecting position and operated to lock the keys by movement of the actuator out of the units selecting position.

14. In a machine of the class described the combination with a series of keys, and adding mechanism including, denomination selecting mechanism having selecting and return cycles of operation, respectively, of transfer restoring mechanism, and key locking mechanism controlled conjointly by the denomination selecting and restoring mechanisms to lock and unlock the keys at the end of said cycles of operation, respectively.

15. In a machine of the class described, the combination with a travelling series of keys, and adding mechanism including denomina-
